UNITED STATES PATENT OFFICE.

JOHN E. MONTELIUS, OF LOS ANGELES, CALIFORNIA.

AERIAL.

Application filed December 27, 1924. Serial No. 758,394.

This invention relates to an improved aerial and seeks, among other objects, to provide an aerial wherein the aerial conductor will be shielded from interfering waves as well as static.

The invention seeks, as a further object, to provide an aerial wherein the aerial coil employed will be surrounded by a shielding cage grounded through a suitable variable resistance which may be adjusted to drain off the interfering or disturbing potential.

And the invention seeks, as a still further object, to provide an aerial embodying a counterpoise and wherein the counterpoise may be adjusted relative to the aerial coil for varying the capacity of the aerial.

Other and incidental objects will appear hereinafter.

In the accompanying drawings:

Figure 1 is a side elevation of my improved aerial.

Figure 2 is a sectional view on the line 2—2 of Figure 1, looking in the direction indicated by the arrows.

Figure 3 is an enlarged detail sectional view particularly showing the aerial coil and cage.

Figure 4 is a transverse sectional view on the line 4—4 of Figure 3, looking in the direction of the arrows.

In carrying the invention into effect, I employ a pair of supports or masts 10 which are erected a suitable distance apart and are preferably of a considerable height. As shown in Figure 2, steel or iron tubing or pipe may be employed for the masts and although I have not so illustrated, appropriate guy wires may, of course, be employed for staying the masts. At the upper ends of the masts are eye bolts 11 and stretched between said eye bolts is a shielding cage embodying a plurality of wires or conductors 12 connected at their ends to suitable insulators 13, and holding the wires apart throughout the major portion of their length are spreaders 14. The spreaders may be of any approved material and, as shown in Figure 4 of the drawings, are preferably circular, while the wires 12 are inserted through the spreaders at equi-distantly spaced points. In the present instance, I have shown the use of a four-wire cage but, of course, this detail may be varied. Connecting the insulators 13 with the eye bolts 11 are short lengths of wire or other suitable flexible elements 15 and leading from one end of the cage is a conductor 16 connected to one terminal of an appropriate variable resistance 17. The conductor 16 is, of course, electrically connected with all of the wires of the cage. The resistance 17 is preferably located near the receiving set so as to be conveniently accessible, and leading from the other terminal of said resistance is a wire 18 which may be grounded to one or both of the masts 10 or directly to the earth.

Centrally supported within the cage is an aerial conductor 19 which is preferably in the nature of a coil, as shown, and the wire employed is resilient so that the coil may be stretched to the desired length. At its ends the coil is, as particularly shown in Figure 3, connected to insulators 20 and extending between said insulators and the insulators 13 are short lengths of wire or other suitable flexible elements 21 for supporting the coil within the cage. Attached to the end of the coil 19 opposite the location of the ground lead 16, is a lead-in 22 which extends to the receiving set.

Centrally supported within the cage is an aerial conductor 19 which is preferably in the nature of a coil, as shown, and the wire employed is resilient so that the coil may be stretched to the desired length. At its ends the coil is, as particularly shown in Figure 3, connected to insulators 20 and extending between said insulators and the insulators 13 are short lengths of wire or other suitable flexible elements 21 for supporting the coil within the cage. Attached to the end of the coil 19 opposite the location of the ground lead 16, is a lead-in 22 which extends to the receiving set.

In conjunction with the aerial conductor and its shielding cage, I provide a counterpoise which includes a pair of spreaders 23 and suitably connected with the spreaders 23 are insulators 24. Connected at their ends to said insulators is a plurality of counterpoise wires 25 and electrically connecting said wires at each end of the counterpoise are cross wires 26. Any approved number of counterpoise wires may be employed and attached to one of said cross wires, preferably at a point midway between the ends thereof, is a lead 27 which is connected to the ground post of the receiving set. Fixed to the spreaders 23 are yokes 28 apertured at their ends to receive the spreaders therethrough. As shown in Figure 2, the yokes are formed to freely straddle the masts 10 and, as brought out in Figure 1, the masts 10 are formed with vertically spaced openings 29 to selectively receive pins 30 extending through the yokes and through the masts for connecting the yokes with the masts. Thus, the yokes are securely anchored to the masts for supporting the counterpoise beneath the aerial conductor in substantially parallel relation thereto while, as will be at once appreciated, provision is made whereby the yokes may be adjusted vertically of the masts for varying the spacing between the aerial conductor and the counterpoise.

and thus varying the capacity of the aerial.

The lead-in 27 is connected to the aerial post of the receiving set so that signals are received directly from the aerial conductor

- 5 19 and I have discovered that by employing a cage for the aerial conductor, as herein described, practically all interfering signal waves are grounded by the cage through the wire 16, resistance 17, and wire 18, and are
- 10 accordingly either materially lessened in strength, as manifested in the circuit of the aerial conductor, or are eliminated altogether. The same has been found true in connection with static. I have further dis-
- 15 covered that by employing the variable resistance 17 in the cage circuit, a means is provided whereby, through the adjustment of said resistance, certain signals may be dissipated or eliminated to the exclusion of others. Accordingly, by changing the ad-
- 20 justment of the resistance 17 as the receiving set is tuned from one wave length to another, pure reception may be had sub-stantially free from interference or static.
- 25 An ordinary potential when used to provide the resistance 17, has been found ample to cover the wave length range of broadcast receiving sets as now on the market.

Having thus described the invention, what

- 30 I claim is:

1. An aerial including spaced masts, an aerial conductor sustained thereby, a counterpoise supported by the masts to extend therebetween beneath the aerial conductor,
- 35 means for adjusting the counterpoise vertically of the masts to vary the capacity of the aerial, and means to coact between said first mentioned means and the mast for locking said first mentioned means in ad-
- 40 justed position.
2. An aerial including spaced masts, an electrically grounded cage anchored at its ends thereto, an aerial conductor supported to extend longitudinally within the cage and shielded thereby, a variable resistance inter-
- 45 posed in the ground lead of the cage, a counterpoise supported by the masts to extend therebetween beneath the aerial conductor, means for adjusting the counterpoise verti-
- 50 cally of the masts to vary the capacity of

the aerial, and means to coact between said first mentioned means and the mast for locking said first mentioned means in adjusted position.

3. An aerial including spaced masts, an ⁵⁵ electrically grounded cage anchored at its ends thereto, an aerial conductor supported to extend longitudinally within the cage and shielded thereby, a variable resistance interposed in the ground lead of the cage, yokes ⁶⁰ straddling the masts, spreaders carried by the yokes, wires insulatingly supported by said spreaders to form a counterpoise extending between the masts beneath the aerial conductor, the yokes being shiftable along the ⁶⁵ masts for elevating or lowering the counterpoise to vary the capacity of the aerial, and means to coact between the yokes and masts for securing the yokes in adjusted position.

4. An aerial including a mast, an aerial ⁷⁰ conductor anchored thereto, a counterpoise, means connecting the counterpoise with the mast whereby said counterpoise may be ad-justed vertically to vary the capacity of the aerial, and means for locking said first men-⁷⁵tioned means in adjusted position, the mast being provided at spaced points with means to selectively accommodate said locking means.

5. An aerial including a mast, an aerial ⁸⁰ conductor anchored thereto, a counterpoise, means connecting the counterpoise with the mast whereby said counterpoise may be ad-justed vertically to vary the capacity of the aerial, and means engageable through the ⁸⁵ mast for locking said first mentioned means in adjusted position.

6. An aerial including a mast, an aerial conductor anchored thereto, a yoke strad-dling the mast, a spreader carried by said ⁹⁰ yoke, a conductor insulatingly supported by said spreader to form a counterpoise extend-ing beneath said aerial conductor, said yoke being shiftable along the mast for elevating or lowering the counterpoise to vary the ⁹⁵ capacity of the aerial, and means to coact between the yoke and mast for securing the yoke in adjusted position.

In testimony whereof I affix my signature.

JOHN E. MONTELUS. [L. s.]
